UNITED STATES PATENT OFFICE.

GEORGE B. KEPLINGER, OF CHICAGO, ILLINOIS, ASSIGNOR TO CRUVER MANUFACTURING COMPANY, OF CHICAGO, ILLINOIS, A CORPORATION OF ILLINOIS.

PERMUTATION LOCK FOR COIN BANKS.

Application filed June 13, 1921. Serial No. 477,093.

To all whom it may concern:

Be it known that I, GEORGE B. KEPLINGER, a citizen of the United States, and resident of Chicago, in the county of Cook and State 5 of Illinois, have invented certain new and useful Improvements in Permutation Locks for Coin Banks, of which the following is a specification.

My invention relates to improvements in 10 receptacles with removable covers and has special reference to permutation locks for coin boxes and the like.

The object of my invention is to provide a small coin bank which shall be in the form 15 of a shallow round box; which shall have one circular end which is removable and provided on its under side with L-shaped locking lugs; which bank shall have a plurality of permutation tumbler rings arranged 20 beneath an annular flange at the open end of the box, one of the rotatable rings being provided with annular projections adapted to contact with the cover and to serve as a guard for the other rings; in 25 which the tumbler rings shall be made of thin sheet metal and provided with edge flanges to strengthen and stiffen them; in which the guard ring shall present a continuous smooth surface to the contents of 30 the box to avoid bunching of the coin or wear on the contents by the rotation thereof; and in which the several tumbler rings shall be held in contact with the body flange by means of lugs or legs stuck up 35 from the bottom cover of the box.

A particular feature of my invention relates to simple sheet metal tumbler rings adapted to set in substantially close contact with each other and a guard ring covering 40 the cover lugs and preventing the coin contacting therewith.

The box body is provided with an inner flange at its open end provided with notches for the entrance of the cover lugs and the 45 tumbler rings are located within this flange, while the guard ring is arranged beneath this flange and is provided at its inner edge with an annular flange spaced from the inner edge of the body flange and adapted 50 to contact with the cover just within the inner edge of the body flange to prevent distortion of the guard ring.

The cover is provided with a dial and the body is provided with a pointer or index so

that the amount of rotation of the cover can 55 be determined accurately and a particular feature of my invention relates to an exceedingly simple means which I have provided whereby I am enabled to produce a plurality of series of banks, each series consisting of an almost endless number of 60 banks, the combinations of all the banks in each series shall have the same ratio but the several banks in each series shall have independent starting and combination numbers 65 to open the banks. Furthermore, by the simple form of tumbler rings which I provide I am enabled to produce three or more series of 70 permutation locks each series having a different ratio and each bank of each series having different sets of numbers though having the same ratio.

My invention will be more readily understood by reference to the accompanying drawings forming part of this specification, 75 and in which:—

Figure 1 is a view in edge elevation of a coin bank embodying my invention;

Figure 2 is a vertical fragmentary sectional view on the line 2—2 of Figure 1; 80

Figure 3 is a fragmentary sectional view on the line 3—3 of Figure 7 showing the several tumbler rings in the unlocking position;

Figure 4 is a similar sectional view showing the locking lug on the cover in the unlocking position; 85

Figure 5 is a sectional view similar to Figure 3 showing the several parts in locking relation;

Figures 6, 7, and 8 are horizontal sectional views on the lines 6—6, 7—7, and 8—8, respectively of Figure 2;

Figure 9 is a fragmentary vertical sectional view on the line 9—9 of Figure 8; 95

Figures 10 and 11 are concentric vertical sectional views on the lines 10—10 and 11—11 respectively on Figure 7;

Figure 12 is a plan view of a blanked out bottom member of the box;

Figure 13 is a bottom plan view of the cover member;

Figure 14 is a perspective view of the body of the box;

Figures 15, 16, and 17 are perspective 105 views of the several tumbler and guard rings;

Figure 18 is a fragmentary sectional view

similar to Figure 9 showing a modified form of tumbler and guard rings; and

Figure 19 is a fragmentary top plan view of the bank showing the means and method 5 of determining the starting number of the opening combination.

The coin bank which I have chosen to illustrate as a typical embodiment of my invention comprises a shallow circular box 1 10 closed at its lower end by a fixed bottom 2 and at its upper end by a removable cover 3. The cylindrical wall of the box is provided at one point with a suitable coin slot 4 and I provide a coin slot guard 5 within 15 the box for preventing the removal of the inserted coin through the slot 4. I do not herein claim the particular form of coin slot guard illustrated, such being disclosed and claimed in my co-pending application filed 20 April 15, 1921, Serial No. 461,518.

The body of the box is provided with a flat inturned circumferential flange 6 at its top or upper end, the inner edge of which is formed downwardly to provide a circumferential inwardly projecting flange 7 thus 25 providing a large central opening 8 at the top of the box within the flange 7 for the removal of the contents after the cover 3 is taken off. The formation of the flanges 6 30 and 7 provides an annular ring-like groove or channel 9 just beneath the upper end of the casing in which I arrange permutation or tumbler rings for locking the cover 3 to the box.

35 The cover is composed of an inner plate 10 which is substantially the diameter of the box and is provided with three L-shaped lugs or projections 11 which are adapted to be entered into notches 12 provided in the 40 inner edge of the flange 6 and through the flange 7 and then to be rotated beneath the flange 7 and thereby lock the cover to the box. The cover is finished at its outer face by a second thin plate 13 which is adapted to 45 be covered by a sheet of celluloid 14 or the like which can be finished in any color and scheme of ornamentation or lettering desired. The outer edge of the plate 13 is downturned to form an annular flange 15 50 which is covered by the celluloid covering and engages the outer periphery of the box for centering the cover on the box. As best shown in Figure 4, the L-shaped lugs or projections are preferably stuck down out of 55 the body of the plate 10 and the cover as a whole is arch shape for stiffness and strength and to increase the capacity of the box.

Within the annular space 9, I provide two 60 tumbler rings 16 and 17 adapted to nest together within the annular ring-like space.

The ring 16 is provided at its inner periphery with three spaced notches 18 and the ring 17 is provided at its inner periphery 65 with similar notches 19. In order that the

cover lugs 11 may pass through the notches 12 the notches 18 and 19 in the rings 16 and 17 must register accurately with the notches 12 in the top of the box. If either of the rings 16 and 17 are shifted around out of 70 registry with the notches 12, the lugs 11 cannot be taken out and the box remains locked.

In permutation locks of this kind as heretofore made, it has been difficult to produce the several members of the locks out of thin 75 sheet metal by the usual manufacturing processes and prevent the discovery, by one not familiar with the combination, of the position of the tumblers by slowly rotating the cover and feeling for the notches. In 80 a lock embodying this invention, such discovery is made impossible by the peculiar form of the tumbler or permutation rings, as the rings are formed to present in all positions except in the unlocking position, 85 flanges which guard the notches 12 and effectually prevent the discovery of the position of any of the notches by the sense of touch.

The tumbler ring 17 comprises a thin 90 ring or band 20 as shown in Figure 5 to fit within the flange 7 and extends from the inner surface of the flange 6 to the lower or inner edge of the flange 7 and consequently when the notches 18 and 19 are 95 out of registry with the notches 12 the lugs 11 cannot be pulled outwardly into the notches 12 to feel them out. This ring 20 is reinforced at the notches 19 by arcuate segments 21, 22, and 23 of varying arcuate 100 lengths for a purpose to be explained.

These segments extend outwardly at right angles to the ring 20 and are formed by first producing a continuous flat flange and then cutting away the portions of the flange 105 between the ends of the segments to provide spaces 24, 25, and 26 of different arcuate lengths between their ends thus providing for different series of permutations, as will appear later. The segments extend outwardly from the upper edge of the ring 20 and are adapted to lie flat against the inner or lower surface of the flange 6. The ends of the segments are bent downwardly as shown in 27 and 28 to form stops which are 110 adapted to be engaged by the ring 16 which will be described later.

The ring 16 has a circumferential flange 29 at its outer edge adapted to lay against the inner cylindrical surface of the body 115 of the box and its upper edge 30 is adapted to contact with the inner or lower surface of the flange 6, and the arcuate segments 21, 22, and 23 are of radial length to contact at their outer edges with the inner surface of the flange 29. The two rings thus 120 operate to hold each other radially between the flange 7 and the wall of the box. The inner edge of the ring 18 is provided with an upturned flange 31 which is just high 125 130

enough to contact the under or lower sides of the arcuate segments as best shown in Figure 3, consequently the lugs 11 cannot pass up into the notches 19 unless the 5 notches 18 register therewith. This construction prevents the location of the notches 19 by the sense of touch.

The flange 31 on the ring 16 also serves another important function, it strengthens 10 and stiffens the ring 16 between the notches 18 thus making it possible to make a practical tumbler ring of this kind out of very thin sheet metal.

To hold the rings 16 and 17 up in their 15 proper positions to contact with flange 6, I provide a guard or protecting ring 32 which is arranged within the box and extends outwardly into contact with the wall of the box. Its inner edge is provided with an outwardly 20 formed circumferential flange 33, the upper edge 34 of which rises to a height where it contacts with the cover when the cover is in place. This flange is located within the 25 circle of the lugs 11 and provides an annular space 35 just within the flange 7 through which the shanks 36 of the cover lugs can rotate. I retain this guard ring 32 in its proper position by projections 39 rising from the bottom of the box just within 30 the circumferential wall of the box. I provide a plurality of these projections 39, preferably four thereof, and form them by blanking out a plate 38 for the bottom with four radial projections 39 at its outer edge 35 and thereafter bend the projections to extend as described, the ring 32 resting upon the upper ends of the projections. I provide space within the guard ring and below the rings 16 and 17 for the outwardly 40 extending portions of the cover lugs and for the interengaging stops or projections which I use to operate the tumblers. Even though the guard ring is made of relatively thin sheet metal, its L-shape in cross-section 45 makes it very stiff to withstand pressure from beneath and as the upper edge of the inner flange contacts with the cover it forms a rigid guard to prevent pressure from the coin being received by the thin tumbler 50 rings which I provide. Furthermore as the cover lugs are entirely covered, they cannot engage the coin and consequently the bunching or abrading of the coin or contents is prevented.

55 The guard ring 32 constitutes one of the elements of the locking scheme and is provided with a struck-up lug 40 which projects outwardly from the base of the inner flange 33 into the path of the cover lugs 11, so that as the cover is rotated the guard ring 60 is rotated whenever one of the cover lugs contacts with the projection 40. It will be understood of course that there is considerable lost motion between the guard ring and 65 the cover upon reverse rotation of the cover

due to the spacing of the cover lugs such lost motion as usual constituting a feature of such combinations.

The guard ring is also provided with a second projection 41 which is stuck up out 70 of the outer edge of the ring and projects inwardly. This second projection is preferably located substantially diametrically opposite to the projection 40 and it is adapted to effect the rotational engagement of the 75 guard ring with the tumbler ring 16 which is provided with two circumferentially spaced stuck up projections 42 between which the projection 41 is arranged. The projections 42, as best shown in Figure 11, are spaced 80 apart to permit suitable lost motion of the guard ring back and forth between them.

For rotationally connecting the ring 16 to the ring 17 I provide the ring 16 with two upwardly extending projections 43 preferably arranged substantially diametrically opposite to the projections 42 and adapted to be arranged in one of the arcuate spaces 24, 25, or 26 of the ring 16 and adapted to engage the down turned ends 27 and 28 of 90 the arcuate segments 21, 22, or 23 as the case may be. By arranging the projections 42 in the different arcuate spaces or by varying the spread of the projections, it is obvious that the ratio of the combinations are 95 changed.

The cover of the box constitutes a suitable dial and is provided on its edge with suitable division marks 44 which can be suitably numbered and the body of the box is 100 provided with an index pointer 45 so that the cover can be turned back and forth known amounts to open the box according to the known combination.

105 Preferably, for a purpose to be explained, I provide one hundred of these division marks on the edge of the cover, and as the celluloid covers are assembled on to the cover members in a promiscuous relation to the cover lugs, there is not a definite or known relation between the lugs and the dial but for any one lug this relation may vary from one to a hundred, and as the registration for opening the box must be within one-half of one of these spaces on the dial, I have by this 110 means provided a range of two hundred different combinations for any series of banks.

115 In assembling the several tumbler rings in cooperative relation, I preferably proceed as follows: The ring 17 is first placed 120 in position with one of the arcuate spaces, for instance the longer one, adjacent to the coin slot and with its notches in registration with the notches in the body. Then the ring 16 is placed in its position preferably with its upturned projections 43 placed 125 in the wide arcuate space 26 of the ring 17 and between the downward projections 27 and 28 on the ring 17 at the ends of said space, and with its notches 18 in register 130

with the notches 12 of the body. The ring 16 has its two downturned projections 42 positioned diametrically opposite to the coin slot and the guard ring is placed in position 5 with its projection 41 between the two projections 42 on the ring 16. Then the bottom of the box is placed in position, the projections 39 rising into contact with the under side of the guard ring and it is thereby held 10 in operative position.

When assembled as described, the cover can be put on, the cover lugs being entered through the several registered notches and upon turning the cover in either direction, one of the cover lugs will engage the control lug 40 on the guard ring. As the rotation of the cover is continued the lug 41 of the guard ring will engage one of the lugs 42 on the ring 16. Then as the rotation of the cover is further continued, one of the lugs 43 on the ring 16 will engage one of the lugs 27 on the ring 17 and each ring in turn will be carried out of register with the notches 12 and with the notches in the 25 other ring thereby effectually closing the notches 12 against the removal of the cover lugs.

It will be understood that the several rings must be held against free rotation so 30 that their movements will be wholly under the control of the cover and for this purpose I so form the rings 16 and 17 that they frictionally engage a relatively fixed surface with sufficient friction to prevent any 35 but intended movement of same. For this purpose I make circumferential cuts 50 at at the outer edge of the ring 16 forming circumferential tongues 51 in the flange 29 which are adapted to be sprung out suf- 40 ficiently to engage the wall of the casing or box and yieldingly hold the ring against free rotation.

To hold the ring 17 I distort the ring member 20 between the arcuate segments 45 and thereby cause it to hug the downturned flange 7 on the box. In the manufacture of the ring 17, this distortion of the ring 20 is caused by the production of the arcuate spaces 24, 25, and 26 which are produced by 50 cutting away the flange between the arcuate segments 21, 22, and 23.

This construction provides a very shallow assembled relation of the tumbler rings in a ring-like space, one of the rings frictionally 55 engaging the cylindrical wall defining the outer edge of this space and the other ring similarly engaging the cylindrical wall which defines the inner edge of the space, and both rings being held against longitudinal or axial movement between the ends 60 of the space by means of the flange 6 at one end and the guard ring 32 at the other end.

In Figure 18 I have illustrated a slight 65 modification. In this form, the guard ring 52 is similar in its shape and function to

the guard ring 32 already described except that it is made more rigid by an outer upwardly extending annular flange 53 which fits within the casing, the free edge of this flange rises into contact with the under side of the flange 6 when the free edge of the inner flange 54 of the guard ring is positioned to contact with the cover. The tumbler ring 16 lies within the flange 53, in fact both permutation tumblers are bridged 75 by this channel shaped guard ring and the pressure of the coin is thus absolutely prevented from reaching these thin rings which I provide, consequently the box can always be opened by one knowing the combination 80 and the pressure of the coin within the box does not affect its operation. The guard ring 52 does not rotate like the guard ring 32 but is fixed and consequently instead of the cover lugs engaging with the guard ring 85 and the guard ring with the ring 16, in this form, the cover lugs engage directly with the ring 16. For this purpose, instead of the projections 42 on the guard ring 16, I provide a projection 54 on the ring 16 in 90 the path of the cover lugs.

As explained herein before, the relation of the dials on the covers is not a fixed relation and to avoid the necessity of making the covers individual to the assembled tumblers and specifying the several numbers of the combination for each specific bank, I arrange a definite known relation 95 between the notches 12 in the box and the cover lugs 11 marking this relation on the 100 dial surface in such a manner that the indication will mean nothing definite to one unfamiliar with the fact. In this manner I can assemble the covers and the banks and by knowing simply the relations of the several combination numbers, I can readily open any bank of the series.

For this purpose, I arrange an indicating mark 55 on the dial as best shown in Figure 19 in a definite relation to the cover lugs 11 on the under side of the cover. I can place this mark or indication at such a point that when it is placed in a definite relation to the arrow indication 45, shown diagrammatically in Figure 19, the cover lugs and the notches 12 will be in register. By this means, I can establish a starting position or number for the particular cover by which I can proceed to open the bank.

As many modifications of my invention 120 will readily suggest themselves to one skilled in the art, I do not limit or confine my invention to the specific details of construction and operation herein shown and described.

I claim:

1. In a receptacle of the kind described, a permutation lock including rotatable tumblers arranged in contact with each other and a guard ring held against endwise move- 130

ment interposed between the tumblers and the interior of the receptacle to hold the tumblers free of excessive pressure.

2. In a coin bank of the kind described 5 rotatable locking rings within one end of the casing, a rotatable guard ring protecting the locking rings from the contents of the bank, a plate closing the opposite end of the bank, projections rising from said 10 plate into contact with the guard ring for rotatably supporting the guard ring in position, and a cover having projections adapted to be engaged with the rotatable locking rings for closing the bank.

15 3. In a coin bank of the kind described rotatable locking rings within one end of the casing, a rotatable guard ring protecting the locking rings from the contents of the bank, a plate closing the opposite end 20 of the bank, the plate formed of sheet metal and formed with radial projections adapted to be bent up to extend through the bank to contact with the guard ring for rotatably supporting the guard ring in position, and 25 a removable cover adapted to cooperate with the locking rings for closing the bank.

4. In a receptacle of the kind described, 30 rotatable permutation rings made of thin sheet metal, the rings provided with notches at their inner edges for permitting the insertion of cover lugs, a guard ring covering the permutation rings and having an inner annular flange spaced from the inner edge of the rings to form an annular channel 35 for the cover lugs, a cover provided with L-shaped lugs for locking the cover on the receptacle, and said flange on the guard ring adapted to contact with the cover when the same is locked to the receptacle.

40 5. In a receptacle of the kind described, the receptacle provided with a circular opening defined by an inwardly projecting annular flange forming a channel, thin sheet metal rings in the channel, a cover having L-shaped 45 locking projections, the flange and locking rings having notches to permit the insertion of the cover lugs when the notches are in registry, a rotatable guard ring within the receptacle covering the locking rings, 50 the guard ring having an inner circumferential flange for contact with the cover and spaced inwardly from the flange on the receptacle to form a protected channel for the cover lugs, the guard ring presenting a substantially continuous and smooth surface to the interior of the receptacle for contact with the contents thereof.

60 6. In a device of the kind described, two notched rotatable permutation rings nested in a circular channel-like space in the casing, the rings formed of thin sheet metal, each ring contacting individually with the bottom of the channel and with the inner and outer circular walls thereof, and each having 65 yielding frictional engagement with one

of said circular walls, a guard ring closing the mouth of the channel and each notched ring having contact with said guard ring, means supporting the guard ring rotatably in position, means rigidly spacing the outer 70 edge of the guard ring from the bottom of the channel, the inner edge of the guard ring formed to extend out past the inner edge of the channel for contact with a cover, as and for the purpose specified.

75 7. A permutation lock for receptacles comprising a cylindrical receptacle and a removable cover therefor rotatable relatively to the body, a plurality of L-shaped projections on the inner face of the cover having 80 their free end portions extending radially outwardly, an L-shaped inwardly extending flange at the mouth of the receptacle having its free end portion opposing the receptacle body and provided with radial recesses 85 corresponding in number, size and relative location with the projections on the cover, the latter adapted to pass through said recesses and engage the lower edge of the L-shaped flange when the cover is turned, a plurality 90 of permutation lock elements mounted to rotate in the channel of said L-shaped flange and having recesses adapted to register with each other and said recesses in said flange to permit mounting and removal of the 95 cover, a rotatable guard ring beneath the locking rings presenting a substantially continuous and smooth surface to the interior of the receptacle, means for holding the lock elements in said channel and the guard ring 100 against said elements, means for limiting the rotation of the locking rings relative to each other, and a projection on the guard ring adapted to be engaged by the projections on the cover for effecting rotation thereof with 105 said cover.

8. In a receptacle of the kind described, thin sheet metal permutation rings nested in a channel in one end of the receptacle, said 110 end of the receptacle having a central opening for the removal of the contents, a removable cover adapted to close said opening, a guard ring within the receptacle for guarding the permutation rings, the guard ring having a central outwardly extending annular flange adapted to contact with the cover as and for the purpose specified.

115 9. In a receptacle of the kind described, one end thereof having a relatively large central opening for the removal of the contents, 120 said opening bordered by an annular inwardly extending flange, tumbler rings within the receptacle having flanges substantially in contact with said receptacle flange, the free edges of all of said flanges being in one 125 plane, all of said flanges provided with recesses, adapted to be brought into register to permit the passage of cover lugs and to be arranged out of register to prevent the passage of cover lugs.

10. In a receptacle of the kind described, a body portion having an opening at one end bordered by a flange, the flange provided with recesses, a removable cover provided with lugs adapted to pass through said recesses in applying or removing the cover, a dial at the edge of the cover and an indicator on the body having a known relation to the recesses for determining the back and forth movement of the cover in the process of opening the receptacle, and an indicating mark on the dial having a known relation to the cover lugs for the purpose of indicating when the lugs are in a predetermined position relatively to said recesses.

11. In a receptacle of the kind described, a body portion having an opening at one end

bordered by a flange, the flange provided with recesses, a removable cover provided with lugs adapted to pass through said recesses in applying or removing the cover, a dial at the edge of the cover and an indicator on the body having a known relation to the recesses for determining the back and forth movement of the cover in the process of opening the receptacle, and an indicating mark on the dial so placed that it is a known number of divisions of the dial removed from the indicator on the body when the cover lugs are in registry with said recesses.

Signed at Chicago, Illinois, this 12th day of May, 1921.

GEORGE B. KEPLINGER.
